[57] **CLAIM**

The ornamental design for a chair, as shown and described.

DESCRIPTION

FIG. 1 is a side elevation view of a chair showing my new design, the undisclosed side being substantially identical with the side shown;

FIG. 2 is a front elevation view thereof;

FIG. 3 is a rear elevation view of my new design;

FIG. 4 is a top view of my new design;

FIG. 5 is an enlarged cross-section taken on line 5—5 of FIG. 4;

FIG. 6 is a cross-section taken on line 6—6 of FIG. 2;

FIG. 7 is a second embodiment of FIG. 1;

FIG. 8 is a third embodiment of FIG. 1;

FIG. 9 is a fourth embodiment of FIG. 1; and FIG. 10 is a fifth embodiment of FIG. 1.

FIG. 10 is a fifth embodiment of FIG. 1.
